UNITED STATES PATENT OFFICE.

JAMES M. PALMER, OF BOSTON, MASSACHUSETTS, ASSIGNOR TO CAROLINE F. PALMER AND WILLIAM L. PALMER, OF SAME PLACE.

VENTILATING RAILROAD-CARS.

SPECIFICATION forming part of Letters Patent No. 578,356, dated March 9, 1897.

Application filed January 20, 1896. Serial No. 576,087. (No model.)

To all whom it may concern:

Be it known that I, JAMES M. PALMER, a citizen of the United States, residing at Boston, in the county of Suffolk and State of Massachusetts, have invented certain new and useful Improvements in Ventilating Railroad-Cars, of which the following, taken in connection with the accompanying drawings, is a specification.

10. The object of my invention is to produce an efficient means for ventilating steam and street cars whereby an adequate amount of fresh pure air will be introduced into the car without drafts, cinders, or dust, while an 15 equal amount of impure or vitiated air will be caused to escape.

The invention consists of air spaces or passages arranged entirely around the top of the car, the longitudinal portion of said passages 20 having openings into the car and the transverse portions having openings under or inlets above the hoods of the car, thus forming air inlets and exits for the air, each of the 25 said longitudinal air-passages being fitted with a central partition that arrests the incoming current of fresh air and compels it to pass out of the front portion of the longitudinal passages into the car, thus supplying it with the desired amount of fresh air and compelling the impure or vitiated air in the car 30 to pass into the rear portion of the longitudinal passages, thence into the rear transverse passages, and out through the opening.

The invention further consists in constructing the windows of the car so that, if desired, a portion of the air may be caused to pass out of the car through said windows, thereby creating a draft that can be felt by the passengers at such openings, but excluding all dust and cinders from the car.

Referring to the accompanying drawings, Figure 1 represents a vertical longitudinal section through a steam-car having a monitor top and fitted with a ventilating device embodying my invention. Fig. 2 is a vertical plan view of same, taken through the monitor top and air-chambers. Fig. 3 is a vertical longitudinal section through a wide vestibule-car, showing an arrangement of 45 tubes instead of an opening under the hood for the admission and exit of the air. Fig.

4 shows a transverse section of a round-top car fitted with a ventilating device embodying my invention. Fig. 5 is a vertical section of one end of same. Fig. 6 represents a partial longitudinal section and side view of a steam-car embodying my invention. Fig. 7 is a horizontal section taken through the monitor top on one side and through the window on the other side. Fig. 8 represents a 60 vertical longitudinal section of a street-car fitted with a ventilating device embodying my invention. Fig. 9 is a horizontal section taken through the monitor top, and Fig. 10 is a vertical cross-section of the same. 65

A represents the car, B B' the transverse air-chambers, and C C' the longitudinal air chambers or passages, each of which is divided in its center by a partition D, said air-channels C C' opening into the car; and the transverse air-chambers are formed with an opening a under the hood that communicates with the atmosphere. By this construction the transverse air-chamber B at one end of the car is in connection with one half C of the 75 longitudinal air-channels on both sides, but at one end only of the car, so that air entering at the forward end of the car into the air-chamber B from the opening a under the hood passes into the air-channels C C' and is arrested by the partition D and passes out through the openings d into the car, and thence passes out through the openings d' into the rear longitudinal air-channels C', thence to the rear air-chamber B', and out through 80 the opening a under the hood. Thus the air in the car is constantly renewed, and that without any perceptible drafts, dust, cinders, or other deleterious matter entering said car.

Should it be desired to ventilate a car having a wide vestibule then of course, the air cannot be admitted into an opening under the hood, in which case I employ three tubes at each end of the air-channels for the admission of the fresh air and the exit of the foul 90 or vitiated air, as shown in Fig. 3.

E represents a tube having a flaring mouth e. The inner end of this tube is surrounded by a tube F of larger diameter, attached to or formed in one with the tube G of smaller 100 diameter that extends down and through the bottom of the car. When in operation, the

fresh air enters the tube E and is conducted and delivered into the tube F above the tube G, and as the inlet-tube E is twice the diameter of the tube G, over which it discharges, the area of said tube G being but one-fourth that of the tube E, by which the air enters, it consequently carries off but one-fourth of the air that enters tube E. The other three-fourths is compelled to pass up the tube F into the longitudinal air-channel C into the car, and of course the impure or vitiated air passes off at the rear end of the car. By this arrangement all dust and cinders that may enter the tube F, being heavier than the air, will follow in the continuous current of air which passes directly from said tube F into and downward through tube G. Thus the car is supplied with a sufficient quantity of fresh air to meet the wants of all the passengers who may occupy the car, and that without dust, cinders, or drafts, as before described.

In Figs. 4 and 5 I have shown my invention as applied to a round-top car. The construction and operation are practically the same as that described with reference to Figs. 1 and 2, except the form of the air-channels CC', which in this case are made of circular form to correspond to the formation of the roof.

In Figs. 6 and 7 I have shown a car ventilated in the manner described with reference to Figs. 1 and 2, but with the addition of windows that can be opened when desired to create a draft that can be felt by the occupants of the car where such windows are opened, but so constructed that dust and cinders cannot enter the same. In this case the windows H are divided into two by means of a central bar *h*, to which the sashes are hinged so as to open outwardly in opposite directions for a short distance, say about three inches; or, if desired, the upper portion of the sash may be fixed, as shown at H', and the lower portion only fitted with a vertical central bar *h*, to which the lower sashes H are hinged to open outwardly. Now should any occupant of the car desire to feel a draft he can open the sash so that it will stand on a slight angle, and a portion of the air that has been introduced into the car through the air-channels or the transoms will escape out of the open window, while the other portion of said air will pass out through the rear longitudinal air-channels.

In Figs. 8, 9, and 10 I have shown my in-

vention as applied to a street-car; but as the construction and operation are the same as that already described no further description is necessary.

What I claim is—

1. In a railway-car a transverse air-chamber at each end of the car, under the hood, each of said chambers communicating with the outer atmosphere and by lateral openings with longitudinal air-channels on each side 60 of the car the ends of which open into the transverse air-chambers, a central partition in each of said longitudinal air-channels and openings from said longitudinal air-channels to the interior of the car substantially as and 70 for the purposes set forth.

2. In a railway-car an air-channel on each side of the car divided at its center by a partition the outer end of one half of both said air-channels communicating by lateral openings with a transverse air-chamber under the hood at one end of the car and the outer end of the other half of said air-channels communicating by lateral openings with a transverse air-chamber under the hood at the other 80 end of the car and an opening, under the hood, to each of said transverse air-chambers for the admission or exit of air, and openings from the air-channels into the car substantially as set forth.

3. In a railway-car a transverse air-chamber at each end of the car, longitudinal air-channels on each side of the car, communicating with said transverse air-chambers at each end, a partition in the center of each of 90 said longitudinal air-channels, an opening under the hood of the car, into the said air-chambers and openings from the air-channels into the car, the area of the openings from the air-chambers into the air-channels being 95 much less than the area of the opening from said air-channels into the car, so that, the air will be distributed into the car at a proportionately less rate or as the areas of the inlets into said air-chambers are to the areas of the 100 openings from the air-channels into the car substantially as set forth.

In testimony whereof I have signed my name to this specification, in the presence of two subscribing witnesses, on this 13th day 105 of January, A. D. 1896.

JAMES M. PALMER.
